UNITED STATES PATENT OFFICE.

ALFRED LOCKER AND EMIL F. GENNERT, OF NEW YORK, N. Y.

AIR-COMPRESSOR PUMP.

SPECIFICATION forming part of Letters Patent No. 501,090, dated July 11, 1893.

Application filed July 22, 1891. Serial No. 400,280. (No model.)

To all whom it may concern:

Be it known that we, ALFRED LOCKER and EMIL F. GENNERT, citizens of the United States, and residents of New York, in the 5 county of New York and State of New York, have invented certain new and useful Improvements in Air-Compressor Pumps, of which the following is a specification.

Our invention relates to improvements in 10 air compressor pumps in which the piston is preferably operated by hand.

The objects of our improvement are first a combination of parts causing the operation to be performed with less labor; second the 15 uniting of the parts to make subsequent adjustment more convenient; third the general construction and combination of parts as hereinafter particularly specified.

Figure 1 is a longitudinal section of the 20 pump. Fig. 2 is a top view and a section of the outlet valve.

Similar letters refer to similar parts in all views.

Upon the base A is mounted the cylinder 25 B. Into the top of the cylinder B is screwed the cap C. Upon the cap C is mounted the frame c. To the frame c at the point c' are pivoted arms c² c³ which at their opposite ends c²⁰ c³⁰ are pivoted to levers c⁴ c⁵ respectively. The levers c⁴ c⁵ extend from their connection with the arms c² c³ across the frame c and are united by a hand piece c⁶. At a point c⁷ between the ends of the arms they are pivoted to the piston rod D.

35 The operation is as follows. The levers c⁴ c⁵ being moved up and down by the hand piece c⁶ force the piston rod D to move correspondingly. When in the position shown in Fig. 1 the hand piece c⁶ and piston d are 40 partially raised and there is but little resistance by the air in the cylinder to downward pressure, so the simple lever movement with fulcrum at c²⁰ c³⁰ is sufficient. As the levers approach the position shown by dotted lines 45 the ends c²⁰ c³⁰ are brought approximately into line with the pivots c' c⁷ and the power of the joint formed by the arms c² c³ and the levers c⁴ c⁵ is brought to bear in forcing the piston d to the bottom of the cylinder when 50 the compressed air offers the greatest resistance. By this arrangement of parts the additional leverage is applied at the time when the most resistance is to be overcome.

The cylinder B is immovably united to the base A, preferably by soldering, to secure an 55 air tight joint at the point of union b, and also to preserve the same relative position of the different parts, that no interference may be caused as sometimes occurs when they are united by a screw, in which case the valve 60 chamber E may be brought into line with the hand piece c⁶, upon the cylinder B being screwed to its seat in the base A. This causes an interference between these parts with incomplete action or injury. It is also desirable 65 that the base and cylinder should always retain the same relative position, as the apparatus when placed for use is arranged in the position considered most convenient.

The base A is formed of the parts a' a². 70 The part a² is secured to the part a' by screws a³. The joint between the parts is made air tight by a packing a⁴. In the part a² is an inlet valve a⁵ which may be of any approved form. In the part a' is an outlet valve e 75 formed of a hexagon rod the edges of which keep the valve central as it moves up and down. The base of this valve is recessed and a packing e' inserted. At e² a stop is placed which limits the motion of the valve in an 80 upward direction. This stop e² prevents the seating of the valve against the upper part of the inclosing chamber which would cut off the outlet of the compressed air. Through the cap C are two openings c⁹ to the outside 85 air to permit the piston to act freely.

What we claim as our invention, and desire to secure by Letters Patent, is—

In air compressor pumps, the combination 90 with the cylinder, piston, and pump-frame, of links pivoted at their upper ends to the upper part of the pump-frame, and the operating lever pivoted to the lower ends of the links and to the piston rod, so that the links and the short arm of the lever form a toggle-joint, substantially as specified.

Signed at New York city, in the county of New York and State of New York, this 15th day of July, A. D. 1891.

ALFRED LOCKER.
EMIL F. GENNERT.
